(57) **CLAIM**

The ornamental design for a splatter shield, as shown and described.

DESCRIPTION

FIG. 1 is an isometric breakout view according to FIG. 2 of the new design of a splatter shield;

FIG. 1A is an isometric breakout view according to FIG. 2 with the handle raised thereof;

FIG. 2 is a top plan view thereof;

FIG. 3 is a front side view, the rear, left, and right being a mirror image thereof;

FIG. 4 is a bottom view thereof; and,

FIG. 5 is a front side view with the handle raised, the rear view being a mirror image thereof.

The broken lines in all views are for illustrative purposes only and form no part of the claimed design.
